ARTIFICIAL TOOTH WITH METAL ANCHORAGE

Hermann Bitter, Osnabrück, Germany

Application March 22, 1955, Serial No. 495,906

Claims priority, application Germany June 15, 1954

5 Claims. (Cl. 32—10)

Artificial teeth for the production of dental prostheses are made of porcelain or plastic. Artificial front and canine teeth are in the form of dental facets of which only the outer surface, front half, labial half, consists of porcelain or plastic. Metal studs or pins, so-called crampons, are used as fixing means and fitted on the flattened rear side of the neck of the tooth. These porcelain or plastic teeth have a very transparent or translucent character, particularly towards the cutting edge. When they are backed with metal, as is customary in the construction of bridges and also in metal settings, the metal shines thru with the result that the color of the tooth is affected in an undesirable manner. To prevent this discoloration it is endeavored to produce a tooth which has a metal anchorage and, without affecting the durability, is so constructed that even at the parts becoming thinner towards the cutting edge, the metal cannot shine thru and cause a discoloration of the dental material.

This object is attained according to the invention by the employment of a U-shaped metal anchorage which is introduced from the neck into the solid body of the artificial tooth, which is provided with suitable recesses, at about the central longitudinal plane thereof in such a manner that its laterally projecting arms only extend so far that they do not allow the material of the tooth to be affected by their presence. The lateral arms of this U-shaped metal anchorage, conforming to the profile of the tooth, are preferably made to taper from the neck towards the point. The two arms of the U-shaped metal anchorage may converge more or less towards the neck of the tooth and even meet in a V-shaped point. Furthermore, the U-shaped metal anchorage may be provided in the middle of its connecting bridge with a pin, to accommodate which a tubular recess is formed in the artificial tooth at the point where it has the most material.

To avoid the necessity of the recesses in the teeth conforming to the exact sectional shape of the metal anchorage, it may be advantageous to provide the U-shaped arms with abutment projections facing one another on the inner side thereof with which they bear against the inner wall of the tooth recesses.

There are several ways of carrying out this solution which greatly facilitates the production. Thus, the lateral tooth recesses may be provided with, for example, spherical recesses at the front ends of their inner boundary surfaces, in which recesses correspondingly shaped spherical projections on the inner edges of the U-shaped arms engage. Balls may also be fitted between the front ends of the projecting U-shaped arms and the recesses in the tooth. This construction represents a very simple and practical method of production.

When making a set of artificial teeth with such teeth and fitting of the teeth in the U-shaped holding members difficulties do not arise as in the case of a U-shaped body with rigidly fixed spherical projections. When fitting a tooth in its U-shaped body it is always necessary to exert a certain amount of force on the U-shaped body in the case of rigidly mounted spherical projections in order

to spread resiliently the arms of the U-shaped metal part to enable them to engage in the corresponding recesses in the tooth. When removing such a tooth from the U-shaped body the difficulties are still greater because in every case an instrument must be inserted as lever between the U-shaped body and the tooth in order to separate the two parts, so that there is always a danger of destruction or damage. In the case of U-shaped bodies with loose balls, these difficulties do not arise. Trial fittings can be carried out without hindrance. When finally fixing such a tooth in its U-shaped body the balls are placed in position and the tooth itself introduced into the mounting with slight pressure to overcome the resiliency of the arms of the U-shaped body. Dental cement is used as binding medium between the U-shaped body and the tooth.

Two embodiments of the invention are illustrated by way of example in the accompanying drawing, in which:

Fig. 1 shows an artificial tooth with metal anchorage according to the invention in front elevation, partly in section on line I—I of Fig. 2;

Fig. 2 is a vertical transverse cross-section of the tooth taken on line II—II of Fig. 1, and

Fig. 3 shows a modified construction taken on a plane similar to that indicated by the line I—I in Fig. 2.

A solid bodied tooth 1 of plastic or porcelain is used. In about the longitudinal middle plane of this tooth a recess 2 is provided which extends to the neck side over the entire width of the tooth and has on each side a portion extending towards the cutting edge so that the recess is approximately U-shaped. The width of this recess, seen transversely to the tooth, is greatest on the neck side and narrows the further it projects at the edges 5, 5' towards the cutting edge.

This recess accommodates a correspondingly U-shaped metal anchorage 3 which fills the recess on the neck side in its entire breadth and has laterally projecting arms 4, 4' which taper towards the cutting edge of the tooth and engage in the lateral extensions 5, 5' of the recess 2 extending towards the cutting edge of the tooth on the side edges thereof.

The lateral extensions 5, 5' of the recess 2 and the arms 4, 4' engaging therein terminate at a distance from the cutting edge, that is, only extend so far towards the cutting edge that there is still in front of them a layer of material of the tooth of sufficient thickness to make it impossible for the presence of the metal to be detected from the outside; for which reason the tapering point or cutting edge of the tooth is entirely free from metal anchorage. The U-shaped construction of the metal anchorage gives the tooth sufficient hold and, through the intermediary of the two projecting arms which nevertheless terminate at a distance from the cutting edge of the tooth, take up the chewing pressure.

At the base of the anchorage 3 the arms 4, 4' can come more or less close together and even meet to form a V-shaped joint.

The U-shaped recess 2 and the metal anchorage 3 with the projecting arms 4, 4' have approximately the same sectional shape. Although slight deviations between the two parts can be compensated by the dental cement which is used when the metal anchorage is finally inserted in the tooth, the fitting is rendered more easy, even when the two cross-sections do not entirely coincide, if the lateral extensions 5, 5' of the recess 2 have at their front ends of their internal boundary surfaces cavities 6, 6' which are, for example, of spherical shape and if the projecting arms 4, 4' of the anchorage have on their inner edges at the height of these cavities 6, 6' projections 7, 7' which are, for example, likewise of spherical shape. Even when the inner edges of the arms 4, 4' do not bear on the inner boundary sides of the extensions 5, 5' along

their entire length, the metal anchorage is given a firm seating by the said projections 7, 7' which, so to speak, interlock in the cavities 6, 6' when the anchorage is introduced into the tooth recess 2. About half way between the two arms 4, 4' the anchorage is provided with a metal pin 10 extending towards the cutting edge of the tooth, which pin engages in a corresponding tubular bore 11 in the tooth.

The same effect can be attained if, according to the construction illustrated in Fig. 3, balls 8 are introduced between the front ends of the projecting U-shaped arms 4, 4' and the inner boundary walls of the extensions 5, 5'. Also in this instance the extensions 5, 5' have on their inner boundary surfaces at the front ends thereof cavities 6, 6' and at the same height as these the projecting arms 4, 4' are provided on their inner side with cavities 9, 9' which are sufficiently large to accommodate the main bulk of the balls 8, which with the portion projecting from these cavities 9, 9' engage in the cavities 6, 6' when the anchorage is slipped into the tooth recess. The material and the shape of the anchorage give the arms 4, 4' sufficient flexibility to yield resiliently in the manner necessary when introducing the anchorage into the tooth recess.

Several such artificial teeth provided with a metal anchorage according to the invention can be united by soldering together the outer edges of the U-shaped arms 4, 4'.

I claim:

1. An artificial tooth comprising a tooth body with a recess of U-shaped section approximately in the middle longitudinal plane, a metal anchorage of U-shaped section inserted and fixed in said recess, and lateral arms formed on said anchorage projecting toward the point of the tooth and narrowing from the neck toward the point of the tooth but terminating at a distance therefrom sufficient to prevent the anchorage from being visible from the outer side through the material of the tooth.

2. An artificial tooth comprising a tooth body with a recess of U-shaped section approximately in the middle longitudinal plane, a metal anchorage of U-shaped section inserted and fixed in said recess, and lateral arms formed in said anchorage converging at least approximately in V-shape toward the neck of the tooth and projecting toward the point of the tooth but terminating at a distance therefrom sufficient to prevent the anchorage from being visible from the outer side through the material of the tooth.

3. An artificial tooth as set forth in claim 1, wherein the lateral recess provided in the tooth has at the front ends of its inner boundary walls cavities of substantially spherical shape and the inner edges of the lateral arms of the metal anchorage are provided with projections at approximately the height of and engaging in these cavities.

4. An artificial tooth as set forth in claim 1, wherein the lateral recess provided in the tooth has at the front ends of its inner boundary walls cavities of substantially spherical shape and the inner edges of the lateral arms of the metal anchorage are also provided with cavities at approximately the height of the cavities in the inner boundary walls of the recess in the tooth, and balls are mounted in the cavities in the tooth and engage in the cavities in the anchorage.

5. An artificial tooth as set forth in claim 1, wherein additional means are provided for securing the anchorage in the tooth body and consist of a metal pin midway between the two arms of the metal anchorage extending towards the point of the tooth, which arm engages in a corresponding tubular bore in the tooth body.
